AUDIBLE RAILROAD SIGNAL

William C. Eaves, Astoria Heights, N. Y., assignor
of forty per cent to Carl H. Fowler, New York,
N. Y.

Application August 14, 1935, Serial No. 36,152

9 Claims. (Cl. 116—142)

My invention relates to a sound device, particularly though not exclusively adapted for an audible railway signal or the like.

When compressed air is directed against an elastic or elastically mounted member, such as a diaphragm through an inlet pipe positioned closely adjacent the diaphragm, the diaphragm will be vibrated due to static air pressure against the diaphragm tending to move the diaphragm away from the inlet pipe and the inherent springiness of the diaphragm or the resilient mounting thereof tending to move the diaphragm back toward the inlet pipe due to the lowered pressure induced by the escape of air from the inlet pipe. Signals involving an air inlet pipe and vibrating diaphragm have heretofore been employed.

It is the principal object of my invention to provide a sound device of the character indicated wherein the efficiency is greatly increased over those heretofore employed.

It is a more specific object to provide a sound device involving an air vibrated diaphragm in which the air employed for vibrating the diaphragm is modulated for the production of sound waves.

It is another object to provide a diaphragm vibrated or held by the action of compressed air and actuated by other means.

Another object is to provide an improved valve arrangement for a sound device of the character indicated.

Another object is to provide an improved form of diaphragm.

Another object is to provide a more naturally balanced sound device both as to construction, design and operation.

Other objects and various features of invention will be hereinafter pointed out or will become apparent to those skilled in the art.

In the drawing which shows, for illustrative purposes only, preferred forms of the invention—

Fig. 1 is a central sectional view through a signal device, such as a railway signal, and illustrating features of the invention;

Fig. 2 is a view in elevation of the valve seat as viewed from the left in Fig. 1;

Fig. 3 is a view similar to Fig. 1 but illustrating a modification;

Fig. 4 is a fragmentary view illustrating the diaphragm, valve seat and associated parts of Fig. 3 as viewed from the left; and

Fig. 5 is a view similar to Fig. 1 but illustrating a further modification.

In said drawing 5 indicates an air-tight casing which may serve as a support for the device. A

valve seat designated generally 6 is secured to the casing and in the form illustrated is secured to an annular plate 7, which is secured as by means of screws 8 to the casing 5. A resilient metallic diaphragm valve member 9 is positioned between the plate 7 and main casing portion 5 and is securely held thereon. The diaphragm is preferably provided with means to prevent the radial movement of its outer edge during actuation. As illustrated, the diaphragm is provided with an annularly extending bead 10, so that when the center of the diaphragm is vibrated or actuated any tendency toward radial movement of the outer edge of the diaphragm where held by the screws 8 will be minimized and a tight joint maintained.

In the particular form shown in Fig. 1 the diaphragm is imperforate and is urged, as by means of a spring 11 adjustable by a screw 12, toward and substantially into contact with the valve seat 6.

The valve seat 6 is of improved form and preferably comprises a plurality of plates 13—14—15, having grid slits 16—17—18 therein, which are arranged in staggered relation so that, as will be later described, the air will be broken up into fine streams and thus more effectively controlled or modulated for the production of effective sound waves. Furthermore, by providing two or more plates the effective grid openings may be readily changed by shifting the plates relatively to each other to vary the size of the passages through said plates. It will be noted that the grid openings in the plates 13—14—15, respectively, are partially offset with relation to each other so that air currents passing therethrough will tend to converge in the expansion chamber 21 within the wall 20 from opposite sides of the center of said plates as air streams and waves flow into said chamber. The bottom of the expansion chamber is preferably about coextensive with the valve and then contracts toward the throat 22, after which it opens out into any suitable horn device.

The diaphragm 10 is vibrated by means of its own inherent resiliency, plus the effect of air directed thereagainst. In the form shown the valve seat 6 is centrally apertured for passage of the inlet end 23 of an air inlet pipe 24. The air inlet end 23 is positioned in contact with or in close proximity to the central portion of the diaphragm 9 and the inherent stiffness of the diaphragm or the adjustable spring 11 or both normally tends to urge the diaphragm into engagement with or in proximity to the inlet end 23, as will be clear. Now, when air under pressure passes through pipe 24 and control valve 25 the static pressure of the air will move the diaphragm 55

9 away from the inlet end 23 and consequently will separate the diaphragm and the valve seat 6. The air will then escape between the diaphragm valve and the valve seat and the air escaping at a rapid 5 rate will lower the pressure at the inlet end 23 permitting the diaphragm to spring back so as to close the space between the diaphragm and the valve seat. The diaphragm will thus be rapidly vibrated, as will be understood. The air dis- 10 charged from the inlet end 23, instead of flowing directly into the expansion chamber, is distributed between the valve seat 6 and the diaphragm and passes through the grid openings in the valve seat in a fairly uniform manner and is modulated 15 effectively and effectively produces sound waves in the expansion chamber, which are contracted in the throat 22 before reaching the expanding horn.

In the particular form shown in Fig. 3 the casing 26 is normally airtight and the diaphragm 27 20 is secured between the edge of the casing and an annular plate 28. The diaphragm may be provided with a bead, as heretofore described. The expansion chamber member 29 is secured to the plate 27 to hold the outer edge of the diaphragm 25 and carries a grid 30, which may be of the same form as that disclosed in Fig. 1 but for convenience is shown merely as a single grid plate. The diaphragm 27 is also provided with grid openings, which are sufficiently staggered in relation to the openings in the grid 30 so that when 30 the diaphragm seats on the grid there can be no escape of air and when the diaphragm is unseated air may escape from either side of the diaphragm through the grid. The diaphragm is 35 preferably provided with other openings 31 to permit the free passage of air to both sides of the diaphragm.

Air for actuating the diaphragm enters through an inlet pipe 32 and an annular passage or groove 40 33 and thence through bores 34 to the diaphragm. The diaphragm, if desired, may be indented, as shown at 35, to form a fairly effective valve to seat with the openings constituted by the bores 34. The action of the vibrating diaphragm in the present instance is substantially 45 the same as that heretofore described in connection with Fig. 1, that is, the air escaping from the bores 34 will vibrate the diaphragm and the escaping air will pass to both sides of the diaphragm and when the diaphragm and valve seat are separated in the vibratory movement of the diaphragm the air will escape from both 50 sides of the diaphragm through the grid valve seat 30, that is to say, since the diaphragm is in the form of a grid valve the air from the airtight casing 26 will pass through the grid valve and then through the grid valve seat, while air on the opposite side of the diaphragm will pass merely through the grid valve seat and the air 55 will thus be modulated and sound waves produced.

It is to be understood that the diaphragm 21 is preferably assisted in its movement toward its seat by a spring 36 backed up by an adjusting 60 screw 37. In order to avoid the possibility of the accumulation of such an excess of air pressure in the casing 26 as would impair the operativeness of the device I prefer to employ an adjustable relief valve 38 for releasing such excess.

In the particular form shown in Fig. 5 the construction of the casing and expansion chamber is substantially the same as heretofore described. However, in this form the diaphragm 40 has a central, substantially imperforate, portion 46 po-

sitioned to normally close the outlet end of the air pipe 45 which enters through the back of the casing 26. The diaphragm is also provided with grid passages 41 to permit air to flow through the same from the expansion reservoir around pipe 45 and within the casing 26 to and through the grid passages in the grid 42. Adjustable springs, such as 43-44, may be provided to assist the diaphragm 40 in a direction to close the pipe 45. A relief valve 38 may be provided in the casing 10 26. In operation air pressure against the diaphragm causes it to become momentarily unseated from the inlet 45, permitting air to flow into the space or expansion reservoir back of the diaphragm 40, from whence it flows through the grid passages by which it is modulated. As the air flows from the pipe 45 into the reservoir back of the diaphragm and thence through the grid passages, the pressure necessarily decreases so that the diaphragm will again return to its seat. In this case the diaphragm does not function to entirely close the passages in the grid 42 and hence rapid vibration of the diaphragm will occur and the rapid, intermittent flow of air through the grid passages will effect the desired 15 20 25 modulation.

While the present invention is described as being embodied in a signal, such as a railway signal or the like, it is to be understood that the air, for example, from the air inlet pipe 24 of Fig. 1 could be employed for maintaining the diaphragm in a fairly balanced position and the diaphragm could be actuated or vibrated by means such as the voice coil of a loudspeaker or the like, so as to cause the escaping air to be modulated in sound reproduction rather than as herein disclosed.

"Air" as used herein means any gas or vapor capable of producing the desired sound effects.

While the invention has been described in considerable detail and preferred forms illustrated, it is to be understood that various changes and embodiments may be made, all within the scope of the invention as defined in the appended claims.

I claim:

1. In a device of the character indicated, a diaphragm valve, a rigid grid valve seat adjacent thereto, and an air inlet pipe having its outlet positioned between said seat and diaphragm valve to direct air against said diaphragm valve to separate said valve and seat whereby air from said inlet pipe will escape between said diaphragm and valve seat and be modulated in passing through said grid valve seat.

2. In a device of the character indicated, a rigid grid valve seat, a diaphragm grid valve for coaction therewith, and air inlet means for directing air under pressure against a part of said diaphragm valve for moving the same in the direction of its seat, said diaphragm valve having passage means for permitting air from said air inlet pipe to flow to both sides of said diaphragm valve and through said grid seat whereby air from said air inlet pipe will pass to both sides of said diaphragm valve and escape through said grid diaphragm valve and valve seat and be modulated thereby.

3. In a device of the character indicated, a grid valve seat, a grid diaphragm valve for coaction therewith, said valve and valve seat being normally spaced from each other, and an air inlet pipe positioned to direct compressed air against said grid diaphragm valve for moving the same in the direction of its coacting seat,

whereby air escaping from said air inlet pipe will tend to close said valve and when said diaphragm valve springs back to tend to close said air inlet pipe, air which has previously escaped from said 5 air inlet pipe will pass through said grid diaphragm valve and valve seat and be modulated thereby.

4. In a device of the character indicated, a rigid grid having a plurality of outlet air passages, a resilient vibratory diaphragm for coaction therewith as a valve, an air inlet pipe positioned to supply air pressure on one side of said diaphragm to unseat it from said grid to permit air to flow through the passages in said grid, an 10 expansion chamber to permit momentary air pressure reduction beyond said air inlet to permit said diaphragm to move in the opposite direction, and adjustable means to vary the speed of vibratory movement of said diaphragm.

20 5. In a device of the character indicated, a valve seat means, a resilient vibratory diaphragm valve for coaction therewith, an air inlet pipe positioned to direct compressed air to one side of said diaphragm for moving the same from its 25 seat, an expansion space beyond said air inlet to permit air pressure to drop beyond said inlet to allow said diaphragm to return, said valve seat means including a grid plate having a plurality of outlet air passages in communication with said 30 space when the diaphragm is unseated, a sound chamber overstanding the outlet side of said grid and contracted toward its outer end, and a horn extending from said contraction.

35 6. In a device of the character indicated, a grid valve seat, a valve for coaction therewith, and means for supplying air for passage past said seat, said grid valve seat comprising a plurality of superposed plates each having grid 40 openings therein, the grid openings of adjacent

plates being arranged in overlapping relationship.

7. In an audible signal, a grid member comprising a plurality of superposed plates having grid openings therein, openings of adjacent plates being arranged in staggered relation, with a sound producing resilient diaphragm co-acting therewith as a valve. 5

8. In an audible signalling means, a casing, a grid plate at one end thereof having a plurality of openings therein, said casing including a sound chamber contracted at its outer end and overstanding all of said grid openings, a resilient diaphragm valve mounted to vibrate in said casing to the rear of said grid plate and having chambers on opposite sides thereof, an inlet pipe for conducting compressed air to one side of said diaphragm to flex it in one direction relatively to said grid plate by air pressure, said valve operating to open and close the passage of air from 10 said pipe to one of said chambers to permit said air pressure against said diaphragm to drop when open to allow said diaphragm to flex in an opposite direction, the passages in said grid plate being in communication with air in said casing 15 while said air inlet pipe is open thereto to permit air to flow through said grid passages for the purpose described. 20

25 9. In a device of the character indicated, a pair of relatively movable plates, both of said plates having a plurality of grid valve openings, passage of air through said openings being controlled by the position of said plates, one of said plates being resilient the other being rigid, and means for directing air under pressure against 30 said resilient plate for vibrating the same relatively to the other of said plates and modulating the air flow through said grid openings of both 35 said plates.

WILLIAM C. EAVES.
